3,453,939 A	7/1969	Pollitz et al.

FIG. 1 is a left side view of a first embodiment of a roof for a road construction machine showing my new design.

FIG. 2 is a front thereof.

FIG. 3 is a right side view thereof.

FIG. 4 is a rear view thereof.

FIG. 5 is a top plan view thereof.

FIG. 6 is a bottom plan view thereof.

FIG. 7 is a top, front, left side perspective view thereof.

FIG. 8 is a top, rear, right side perspective view thereof.

FIG. 9 is a left side view of a second embodiment of a roof for a road construction machine showing my new design with the side canopy portions shown in a closed condition.

FIG. 10 is a front view thereof.

FIG. 11 is a right side view thereof.

FIG. 12 is a rear view thereof.

FIG. 13 is a top plan view thereof.

FIG. 14 is a bottom plan view thereof.

FIG. 15 is a top, front, left side perspective view thereof; and, FIG. 16 is a top, rear, right side perspective view thereof.

The broken line showing of the bottom areas of the roof is included for the purpose of illustrating portions of the roof for a road construction machine and forms no part of the claimed design.
